UNITED STATES PATENT OFFICE.

RALPH WHITLEY, OF PATERSON, NEW JERSEY, ASSIGNOR OF ONE-HALF
TO JOSEPH FAIRHURST, OF SAME PLACE.

SWIVEL BATTEN AND SHUTTLE FOR LOOMS.

SPECIFICATION forming part of Letters Patent No. 608,816, dated August 9, 1898.

Application filed March 12, 1897. Serial No. 627,257. (No model.)

To all whom it may concern:

Be it known that I, RALPH WHITLEY, a citizen of the United States, residing in the city of Paterson, in the county of Passaic and State 5 of New Jersey, have invented certain new and useful Improvements in Swivel Battens and Shuttles for Looms; and I do hereby declare the following to be a full, clear, and exact description of the invention, such as will enable 10 others skilled in the art to which it appertains to make and use the same, reference being had to the accompanying drawings, and to letters of reference marked thereon, which form a part of this specification.

15 My invention is an improvement in the construction of the swivel batten and its corresponding shuttles as they are known in the silk-weaving industry to-day.

In order to more thoroughly understand 20 wherein my mechanical improvements consist and how they effect the woven fabric, it will be necessary to review that part of the silk-weaving industry relating to weaving by means of the swivel action, so that not alone 25 the mere innovation in the mechanical construction may be understood, but so as to fully and clearly bring the object of my invention to the public—viz., that of introducing the art of embroidery into woven fabrics 30 simultaneously with the weaving.

“Swivel-weaving,” as it now is known, is an imitation of embroidery, but to the present day a very limited and imperfect imitation. The reason for this is that a certain 35 space occupied by the shuttle could not possibly be covered by swivel-work. Consequently the first and principal aim of my invention was to reduce that uncovered space in the fabric as much as possible. I have 40 gained not alone a reduction of that space, but by the peculiar and entirely novel construction of the shuttles and their movement in the batten relative to the same and each other the said space has been so much reduced 45 that what would formerly, even with the smallest possible construction of a shuttle, still remain an open space all the way longitudinally through the fabric now disappears entirely, so that no channels or spaces will 50 be visible, because by means of the close proximity of the shuttles to each other the whole

fabric will be homogeneous in its design—in other words, will appear as if it had been subjected to the operation of an embroidery-machine. In saying this I define still 55 more clearly the object in my invention—viz., that by my improved swivel mechanism I can during the process of the weaving introduce that embroidery-work which heretofore had to be done by a special embroidery-machine 60 after the fabric had left the silk-loom.

It will, after the foregoing explanation, now be plainly understood that designs can be woven into the fabric at any point lengthwise or breadthwise, inasmuch as a breadthwise continuous design can be interwoven 65 throughout the whole surface for a certain length, after which the swivel action can be stopped and then continued farther down, which will find a ready application for border-work on silk skirts, table-covers, &c. Last 70 but not of least importance is the fact that on account of the reduced spacing between the individual patterns more color can be introduced. This I can illustrate very plainly by 75 stating that, for instance, in a piece of fabric twenty inches broad it was possible by the old style of swiveling only to weave nine figures, whereas with my improved swivel mechanism thirty-six figures can be woven in, and 80 consequently it is possible on the same space to introduce more colors as well as designs, the result being that it will open the door for richer and more varied patterns both in design and color by very much cheaper means. 85

In describing my invention I shall call attention to the accompanying drawings, wherein like letters of reference indicate corresponding parts in the different views, and wherein—

Figure 1 shows a front view of my improved 90 swivel mechanism; Fig. 2, an enlarged view of one end of my mechanism; Fig. 3, an end view of Fig. 2; Fig. 4^A, a sectional view on line *xx* of Fig. 2, showing one of the teeth *A*³ of the swivel-beam; and Fig. 4^B, a front 95 view of Fig. 4^A; Fig. 5, a top view of the spacing-bar *H'* shown in Fig. 2; Fig. 6, a top view of the spacing-block *L'*; Fig. 7, an end view of the spacing-block shown in Fig. 6; Fig. 8, an end view of the spacing-bar; Fig. 9, a front 100 view of my improved swivel-shuttle; Fig. 10, a side view of the same; Fig. 11, a top view

of my improved shuttle as shown in Fig. 9; and, finally, Fig. 12 is a sketch of the old style of swivel batten and shuttles, inserted for the sake of clearness in explaining the difference between the old and new style of swivel-batten.

In Fig. 1, A indicates what is known as the "swivel-batten," which is connected by arms O' and O² to the loom, as usual. The up-and-down motion, consisting in letting it down into and drawing it up out of the shed, is performed by the usual mechanical means. Furthermore, the right-and-left movement of the old swivel-shuttle-actuating rack, similar in its operation to my swivel-shuttle-actuating bars B⁷ and B⁸, is operated in the customary manner by means acting on the lugs P' and P², giving them an alternating right and left movement. As these two motions are old and familiar in looms and as the whole combination of mechanical means causing them to exist in several kinds of looms form no part of my invention and have, further, been found subject for improvements protected by Letters Patent at various times the above allusion to them will be sufficient for my purpose.

My improved swivel-batten A is cut out on the lower edge, turning toward the fabric with tooth-like indentations called A' A² A³ A⁴, and so on. Said teeth, as seen in the illustrations, are pointed at the bottom, so that they may easily part the silk threads, and the space between each pair of teeth is for the reception of the silk threads parted by the aforementioned points of the teeth. Taking one of these as an example of them all—for instance, A³ (shown separately in Fig. 4^A)—it will be seen that it has a groove C, said groove being partly closed at the top in front by the part D, which, as will appear later, acts as a guide for the shuttles. Moving on the front face of the swivel-batten A are the shuttle-actuating bars B⁷ and B⁸, which, being each furnished with two slots, respectively F' F³ and F² F⁴, are held up against the batten by means of screws E' E³ and E² E⁴, having disks G' G³ and G² G⁴ lying, respectively, between their individual screw-heads and the batten. The bars B⁷ and B⁸ are furnished with prongs B' and B², each of which prongs (see Fig. 2) has two holes, said holes admitting, respectively, pins B³ and B⁴, secured to the spacing-bar H' and B⁵ and B⁶ to the spacing-bar H², (see Fig. 1,) both of which spacing-bars move in the groove C. By the aid of these connecting means it is apparent that the bars B⁷ and B⁸ and the spacing-bars move together as one part. The said spacing-bars H' and H² have each an inclined surface I, as best seen in Fig. 5, the function of which element will be explained later on. On each of two lateral projections or arms on the batten A springs J' and J² are secured, one end of each of said springs resting against and acting upon the respective prongs of the bars B⁷ and B⁸. A second set of springs K' and K² are

suitably attached to the batten A, each of which springs rests against and co-operates with its respective spacing-bar H' and H². Lying between the spacing-bars H' and H² and the first shuttle in the row on each side of the batten and conformed to the groove C so as to move in it are two spacing-blocks L' and L². Moving in the groove C of each of the batten-teeth is a shuttle, one shuttle corresponding to each tooth, consequently M' in A', M² in A², M³ in A³, and so on. As they are exactly alike the description of one will suffice for them all, and I will therefore proceed to describe the shuttle M³, depicted in a front view in Fig. 9, as it is seen in Fig. 1, a side view shown of it in Fig. 10, and a top view in Fig. 11. Said shuttle will be seen to consist of two main parts—a front part Q and a rear inside part Q'. The front part Q is pear-shaped at the top, constructed so as to correspond to the lower part of the tooth A³ and for the same purpose—viz., to present a good sliding surface for the threads, so that no thread can be caught or held by it, resulting in the same number of threads being maintained on each side of the tooth after the shuttle has passed from one tooth to another. The rear part Q' is shaped so as to conform to the groove C, having to that effect a groove Q², that has the part D, or, as it might be called, the "guide" D, of the tooth A³ moving in it to steady it and guide it from one tooth to another. Projecting from the front part Q is a pin R, having a loose sleeve S mounted thereon. Finally, the bobbin or reel T, having the silk wound on it, is mounted on the sleeve S, and in order to secure said bobbin on the sleeve U is attached between the front part Q of the disk R and bent, as illustrated, so that at the same time it regulates the unwinding of the thread it also has a tendency to keep the bobbin on the sleeve.

The operative method of the above-described elements is as follows: It will be readily seen that in order to move the shuttles back and forth through the silk web new operative means have been introduced. In this fact lies my reason for calling the elements B⁷ and B⁸ "swivel-shuttle bars" and not a "swivel-shuttle rack," inasmuch as the term "rack" denotes a mechanical element furnished with teeth, in which case the shuttles were also furnished with teeth, and pinions lying intermediate between the shuttle-rack and the teeth in the shuttles actuated the shuttles. Other means are also employed to move the shuttles back and forth—for instance, one single pin is fastened to each shuttle, which pin forms part of the swivel-actuating rack. By these latter means the shuttles are moved in the sketch shown in Fig. 12.

The main constructional point in my invention can consequently be sought in the above statement, it being this—that based on the distinctive and peculiar construction of each

of my improved swivel-shuttles all of the shuttles will move simultaneously to the right and to the left when a motive power is applied to the end shuttle on each side. This movement is administered by my improved swivel-shuttle bars B^7 and B^8 . The next important step in my construction is the support of these mutually-cooperative shuttles in some new form of batten. This improved batten 10 A has, as described above, a row of teeth, each of which teeth supports in its groove C a shuttle, and the distance for the shuttle to travel is consequently the distance marked Y in Fig. 2, from the center of one tooth to the center of another. It will now be clearly understood what is meant by the "reduction of space" alluded to in my preamble and how no longitudinal spaces or channels will be visible in the fabric, but, on the contrary, 15 that a design can be spread evenly throughout the whole fabric, simply because the space occupied by the shuttle has been so far reduced that the resulting bare channels on the fabric become too small to attract attention. 20 The smallest shuttle known in the old style of swivel-weaving occupied a space of at least one and three-quarters inches, whereas my shuttle occupies a space of less than half an inch and can be constructed on a 25 smaller scale, if it should be desired, the mere diminishing of any of the dimensions in my improved swivel mechanism of course not altering my inventive idea. Lying between the arms B' and B^2 of the swivel-shuttle-actuating bars B^7 and B^8 and the extreme shuttle at each end are the two spacing-bars H' and H^2 and the spacing-blocks L' and L^2 , and 30 acting on the respective arms B' and B^2 are, furthermore, springs J' and J^2 . If now a power be applied simultaneously to the right and left lugs P' and P^2 and the batten be sunk into the web, the natural result will be that taking a movement from the left side to the right side in Fig. 1 the bars B^7 and B^8 35 will be moved in the direction of the arrowhead V , the arm B' will act on the spacing-bar H' , attached to it by means of pins B^3 and B^4 , which in its turn will act upon the spacing-block L' , and L' will move the adjacent shuttle A^3 , A^3 will move A^4 , A^4 A^5 , and so on the 40 whole row through. The space moved will consequently be, as before stated, just the space Y from one center to another. If there were no spring J^2 at the other end when the bar B^7 caused the shuttles to move from left to right, a complete standstill of the shuttles or a dead stoppage of these would be the result and no revibration between them would be perceptible, but each shuttle would stop 45 where its companion left it, and as that might happen to be out of the center line of the tooth it might cause confusion in the web, and the threads might be caught by the shuttles when drawn up again for another pick. To obviate this, the reciprocating springs J' and J^2 50 are provided, so that, alluding to the above-described action in the direction of the arrow-

head, when bar B^8 arrives at its terminal, limited, of course, by the length of the slits F^2 and F^4 , it is given an elastic reactionary movement by the spring J^2 . At this point the inclined surface I on the spacing-bar H^2 comes into play simultaneously with the action of the spring K^2 , pressing against said surface. If this spring K^2 did not exist, the action of the spring J^2 would throw the shuttles too far back; but as the spring K^2 rests on this inclined surface the sudden action of the spring J^2 is broken. As the lowest part of the inclined surface is gradually forced in under the spring K^2 it will readily be seen that any sudden reaction on the shuttles is avoided; but by this last action a touch has been administered to the spacing-block L^2 , enough to send it over toward the shuttles, which will permit 70 them to adjust themselves, so that by means of the threads contacting with the shuttles' oval sides as they are drawn out of the web they will settle back again toward the spacing-block L^2 , which said block permits, as a 75 space has been provided for between the spacing-block and the spacing-bar for that purpose. When these different parts are constructed and fitted to each other in the above-described manner, it has been found by actual 80 experiment that the shuttles will resettle themselves after each movement of the swivel-shuttle bars B^7 and B^8 back and forth, so that the center point of the front part Q on each shuttle will be in the center of each tooth of the batten A . If this movement on the part 85 of the swivel-shuttle bars B^7 and B^8 be continued back and forth, the thread on the spool T will be woven into the fabric between the teeth A' , A^2 , and A^3 , and so on, in the swivel-batten A , which was the desired object I had in view. 90

In conclusion I might add by way of elucidation, taking the sketch of the swivel batten and shuttles illustrated in Fig. 12 as an average example of the swivel-batten now used, that when observing the space between the shuttles in Fig. 12, (marked W), representing in actual measurement two inches, for instance, and comparing it with the one-half-inch space referred to before between the centers of each pair of shuttles in my improved batten (marked W') the reduction in space referred to is self-evident. 110

That various minor constructional details 115 in my improved swivel-batten may be altered and improved upon without disturbing my inventive principle of separate, loose, and mutually contacting coacting shuttles is apparent—for example, the springs J' and J^2 120 may be subject to improvements and other means might be found more practical than the spacing-bar and block system here described.

Having thus described my improved swivel-batten and swivel-shuttles, what I claim, and desire to secure by Letters Patent, is— 125

1. A batten having a series of loose, mutually contacting and coacting shuttles, lin-

early arranged with regard to each other, suitably supported in said batten, and means operating on the end shuttles of the series for the purposes as set forth.

5 2. A series of loose, mutually contacting and coacting shuttles, linearly arranged with regard to each other, a batten furnished with a series of teeth having guiding-grooves supporting the shuttles, a shuttle-shifting bar, 10 springs acting on said bar and means to move the bar to shift the shuttles.

3. A series of loose, mutually contacting and coacting shuttles, linearly arranged with regard to each other, a batten furnished with 15 a series of teeth having guiding-grooves supporting the shuttles, a shuttle-shifting bar, secured to the batten, means to move the same, springs controlling said shifting-bar and spacing means interposed between the 20 shifting-bar and the shuttles for the purposes as set forth.

4. A series of loose, mutually contacting and coacting shuttles, linearly arranged with regard to each other, a batten having thread 25 gathering and confining spaces cut out in the lower edge thereof, and a guiding-groove supporting the shuttles, a shuttle-shifting bar secured to the batten, a right and left arm depending from said shifting-bar, a buffer-

spring acting on each of said arms, a spacing-bar secured to each shuttle-shifting-bar arm, springs controlling said spacing-bars, spacing-blocks moving in the batten-groove lying between the spacing-bars and the end shuttles, for the purposes as set forth, substantially as described.

5. The combination in a loom of a swivel-batten having downward-projecting parts terminating in a smooth, pointed apex, thread gathering and confining spaces furnished between each two projections, a guiding-groove for the swivel-shuttles running throughout the length of the batten-beam, said guiding-groove having an upper guide, a swivel-shuttle-operating bar secured to the swivel-batten, means to move it, contacting swivel-shuttles adapted to move in the guiding-groove of the swivel-batten, bobbins suitably supported on each shuttle, for the purposes as set forth, substantially as illustrated and described.

In testimony that I claim the foregoing I have hereunto set my hand this 29th day of August, 1896.

RALPH WHITLEY.
